GAS RELEASE MECHANISMS

Lionel E. Goff, Alton, Ill., assignor to Clin Mathieson Chemical Corporation, East Alton, Ill., a corporation of Virginia

Filed Aug. 31, 1960, Ser. No. 53,218

1 Claim. (Cl. 102—25)

This invention relates to gas release mechanisms and more particularly to such devices adapted to effect the sudden release of a charge of compressed gas to serve as a work performing medium. While such devices are applicable to many commercial applications, the present invention will be described with particular reference to blasting cartridges utilizing compressed gas. This application is a continuation-in-part of Serial No. 828,812 filed July 22, 1959, now abandoned.

Material breaking cartridges using compressed gas to execute the required work are well known and widely used in the mining industry. Such cartridges or blasting devices are all reliant upon the sudden release of compressed gas to give a quasi explosive effect. The predecessors of this type of blasting cartridges consisted essentially of a cylindrical gas containing cartridge having venting means. The cartridges were charged with gas under considerable pressure, sealed and then conveyed to the face to be worked. The compressed gas within these cartridges was released by elaborate remote control means. More recently, the practice has been to place an uncharged cartridge in the bore hole and pump gas through a suitable conduit into the cartridge in situ. Conventionally, these cartridges are formed of high strength materials and are provided with a relatively weak member which shears or ruptures so as to liberate the gas from the cartridge body. Since the amount of pressure that can be built up in the cartridge body is dependent upon the strength of the expendable member, the quantity of energy developed by the liberation of the gas can be controlled within relatively close limits. Such cartridges are generally satisfactory but have one serious inherent drawback. After each shot, the discharge end of the cartridge must be dismantled to remove the expendable portion which has ruptured or sheared and to replace it with a new one.

This shortcoming has been well recognized and has led to a concerted effort for the development of automatic shells. While many so-called automatic shells have been presented, they have met with only a modicum of success. The previous types of automatic cartridges are operable, but they are very heavy, complex and unreliable. Although the expendable portions of the shell have been eliminated, this elimination has introduced new and more serious problems. Normally, the known automatic shells rely upon a series of two or more control or pilot valves to initiate the main release valve. Such complexity of design leads to cartridges that are difficult to control and exceedingly difficult to discharge at a desired predetermined pressure. In addition, the great number of moving parts in the automatic shells prior to the advent of the present invention has confronted the industry with a formidable sealing problem.

Therefore, it is an object of this invention to provide new and improved automatic or semi-automatic devices for releasing compressed gas. A further object is to provide a device of this character having novel gas release means. Another object of this invention is to provide a simplified automatic or semi-automatic blasting shell overcoming the disadvantages of the prior art.

The manner in which these and other objects are achieved will be apparent from the following specification together with the drawing in which:

2

FIGURE 1 is a longitudinal sectional view of a device illustrating a preferred embodiment of this invention;

FIGURE 2 is a longitudinal sectional view of a modification of the device shown in FIGURE 1;

FIGURE 3 is a longitudinal sectional view of a device illustrating another embodiment of the present invention;

FIGURE 4 is a longitudinal sectional view illustrating an additional modification of the present invention;

FIGURE 5 is a longitudinal sectional view illustrating still another embodiment of the present invention; and

FIGURE 6 is a longitudinal sectional view of another modification of this invention.

The same numbers are used throughout the drawing to identify similar components.

Referring to FIGURE 1 which illustrates a preferred embodiment of the present invention, an elongated tubular body formed of metal, fiber glass reinforced plastic, or other material of a strength to contain gas under high pressures, for example in the range of from 6,000 to 20,000 pounds per square inch, is indicated generally at

1. Suitable means such as a compressed air inlet 48 are provided at one end of the cartridge body for introducing compressed gas into it. The outer diameter of the body is such that it may be set freely within a bore drilled in the face of the material, such as coal, to be mined and broken down. The end of the body 1 remote from the gas inlet is screw threadedly attached to sleeve 2 as indicated at 3. The seal between these two components is completed by resilient O-ring 4. The other end of the

sleeve is closed with end plug or cap 5 which is screw threadedly attached to sleeve 2 as indicated at 6 with the seal between these two members also being completed by resilient sealing means, such as O-ring 7. The interior of the cylindrical body is divided into a main chamber 8 and a second chamber 9 by main valve 10 which is slidably in the body. The valve is normally maintained in a closed position spanning lateral discharge ports 11 by helical spring 12 positioned in annular space 13 between sleeve 2 and central extension 14 of end cap 5. The valve is slidably sealed to the central extension 14 of the end cap by resilient sealing means, such as O-ring 15.

As shown in the drawing, the base portion 16 of the valve is provided with passageway 17 so as to maintain the pressure within chambers 8 and 9 substantially equal while the chambers are being charged with compressed gas. Valve 10 is also provided with one or more lateral vents 18 in the area of reduced diameter adjacent the base of the valve. The valve is normally held in sealing relationship with metallic seal ring 19 which is slidably sealed to sleeve 2 by suitable resilient means such as O-ring 20. Metallic sealing ring 19 is responsive to the pressures built up within main chamber 8 but is restricted in its movement by its abutment with tubular body 1 and also by shoulder 21 of sleeve 2. As shown in the drawing, the sealing ring 19 terminates in a modified knife edge 22 at its point of contact with shoulder 23 of the sleeve valve. The knife edge is carefully machined and polished or otherwise constructed to insure the formation of a metal-to-metal seal between the metallic sealing ring and the valve.

Although such a knife edge is preferred, the forward end of the ring 19 can be otherwise constructed such as square so as to provide a flat metal-to-metal seal with shoulder 23 of valve 10.

While the sealing ring 19 is shown as a member separable from and movable in relationship with main body 1, the ring can be rigidly positioned between the main body and shoulder 21 on the sleeve. Alternately, the inner portion of main body 1 of the cartridge can be modified to form an immovable valve seat for main valve 10.

With such construction, it is necessary to maintain the proportions and design such that an effective seal with valve 10 is had during the gas charging operation. Be-

65
70

cause of minor inherent surface irregularities, the construction is such that the enlarged basal portion of the metallic sealing ring 19 and the end of body 1 do not form a seal. Thus, under the high pressures encountered, the entire base surface of metallic sealing ring 19 is subjected to the pressure within main chamber 8.

The internal diameter of metallic seal ring 19 is larger than the outside diameter of the basal portion 16 of the valve 10 so as to form a small clearance between these two components. If this clearance is made sufficiently large, sufficient air from the main chamber will pass therethrough into the second chamber 9 so as to equalize the pressure within these two chambers. In such instances, passageway 17 in the base portion of the valve 10 can be eliminated.

The cartridge of this embodiment is so designed that the valve 10 has a greater effective area exposed to the gas pressure in the main chamber 8 than to the gas pressure in the second chamber 9. Also, the effective area of the metallic sealing ring 19 exposed to gas pressure is greater at that end proximate the main body 1 than at the other end. These differential areas of valve 10 and metallic seal ring 19 cause them to move in a direction away from the main body 1 as the pressure within the cartridge is increased.

In operation, compressed air or other suitable gas is introduced into main chamber 8 through gas inlet 48. The air passes through passageway 17 and lateral vents 18 in main valve 10 into the second chamber 9. Thus, the pressure on either side of main valve 10 is substantially equalized and is maintained equal throughout the charging operation. Because of the greater effective cross-sectional area of valve 10 and metallic seal ring 19 in the main chamber than in the second chamber, the valve and the ring are urged in a direction toward end cap 5 in opposition to helical spring 12.

This sliding movement of valve 10 and seal ring 19 continues until a predetermined discharge pressure, for example about 9,000 pounds per square inch, has been built up in chambers 8 and 9. At this point, further movement of the metal seal ring 19 is prevented by its contact with shoulder 21 on sleeve 2. Continued movement of the valve 10 causes a separation of the valve from the metallic seal ring 19. This separation has two instantaneous effects: an increase in the effective area of the main valve exposed to the pressure in main chamber 8, and a reduction of gas pressure in chamber 9 by gas being vented through lateral vents 18 and exhaust ports 11. Thus, the pressure in second chamber 9 is reduced at such a rapid rate that it cannot be balanced by gas from the main chamber entering through passageway 17 and/or from around the periphery of 16 through lateral vents 18. The pressure in the main chamber 8 is thus suddenly unopposed and the main valve 10 is moved rapidly unsealing lateral discharge ports 11. Any compressed gas remaining in the second chamber 9 is exhausted through lateral vents 18 and exhaust ports 11. With the sudden reduction of pressure within the second chamber 9, the charge of compressed gas in main chamber 8 is completely and instantaneously released through ports 11 to the surrounding work face which is to be broken down.

Upon discharge, the annular space 13 between central extension 14 of the end cap and sleeve 2 serves as an air cushion which prevents the valve 10 from setting up disruptive forces upon discharge by coming in contact with the end of the cartridge. While the air within this annular space does serve as a cushion, it does not hinder the opening of the valve because the compressed air can escape at a reduced rate through the annular clearance 24 between the outside diameter of valve 10 and sleeve 2.

After the compressed gas in main chamber 8 has been completely discharged, the valve is returned to its original position by helical spring 12. This also causes the me-

tallic seal ring 19 to be again abutted on the end of tubular body 1. The device is then in position for another discharge. Thus, this embodiment of the present invention is completely automatic.

The embodiment illustrated in FIGURE 2 is similar to that of FIGURE 1 but differs therefrom in a number of respects. It will be noted that valve 10 is slidably sealed to sleeve 2 by means of resilient O-ring 25 rather than being internally sealed to central extension 14 as was the valve of FIGURE 1. Also, the clearance between metallic seal ring 19 and the basal portion 16 of the valve 10 has been materially reduced. Thus, substantially all of the compressed gas entering second chamber 9 from main chamber 8 passes through passageway 17 in the base of the valve 10. In addition, the configuration of valve 10 is modified. It is provided with a lateral extension 27 which abuts metallic seal ring 19, and the external diameter of the valve above and below this extension is substantially the same.

The cartridge of this embodiment functions in substantially the same manner as described above. As the pressure in chambers 8 and 9 is increased to the predetermined discharge pressure, metallic seal ring 19 is stopped from further sliding movement by shoulder 21 on sleeve 2 while the valve continues its sliding movement breaking the seal between these two members. Here again, valve 10 is suddenly opened by the rapid reduction in pressure in chamber 9 by gas escaping through lateral vents 18 and ports 11 and also by the increase in the effective area of the valve in contact with the pressure in main chamber 8. The valve continues its sliding action to a fully opened position at which point extension 27 on the valve contacts shoulder 26 on the inside surface of sleeve 2. Disruptive contact between the valve and sleeve is prevented by gas which is temporarily trapped within annular space 28 between the valve and the sleeve. This delaying action of the annular space is transitory because the gas can escape at a reduced rate between extension 27 and sleeve 2 and thus be exited through lateral discharge ports 11. Here again, the action of the shell of this embodiment is completely automatic and the valve and seal ring are returned to their original closed position by helical spring 12. Here, again as in the embodiment of FIGURE 1, passageway 17 may be omitted and the clearance between sealing ring 19 and basal portion 16 of the valve can be made sufficiently large to substantially equalize the pressures in chambers 8 and 9 during a charging operation but insufficiently large to permit such equalization of pressures when the seal between ring 19 and extension 27 is broken by movement of valve 10.

In the embodiments shown in FIGURES 3 through 5, the main valve 10 is provided with lever or triggering means to accentuate and accelerate the separation between the valve 10 and the metal seal ring 19. In the embodiments of FIGURES 3 and 4, linkages are provided to momentarily arrest or reduce the closing influence of springs on the sleeve valve. In the embodiment shown in FIGURE 5, the separation of these two components is accelerated by a lever linkage cooperating with the basal portion of the sleeve valve. Such lever mechanisms insure a rapidly accelerated breaking of the seal between the sleeve valve and the metallic seal ring, even at rather low pressure levels or when the differential areas of the valve and metallic seal ring are at a minimum. The embodiments illustrated in these three figures will now be described separately.

In the embodiment illustrated in FIGURE 3, means have been added to interrupt the closing influence of springs on valve 10. In this embodiment, the end of the sleeve valve 10 remote from the basal portion 16 thereof is spanned by disc 29 having one or more perforations 30, and the valve is slidably sealed to sleeve 2 by O-ring 25. Bolt 31 passing through disc 29 terminates in clevis 32, and the valve is connected to spring plate 33 through connecting link 34 and pivot link 35 as shown. These mem-

bers are so connected that pin 36 is slightly below the axis of pins 37 and 38. Thus, any movement of valve 10 and the action of control spring 39 tends to rotate pivot link 35 in a counterclockwise direction so as to lock the linkage. The pivot link 35 is provided with an extended portion 40 adapted to cooperate with stop pin 41 which extends across the internal portion of sleeve 2 and is rigidly affixed thereto by any suitable means. Control spring 39 is affixed to spring plate 33 as indicated generally at 42. In addition to central extension 14, end cap 5 is also provided with a tubular extension 43. These two extensions of the end cap serve as guides for helical spring 12 and also for control spring 39.

In operating the cartridge shown in FIGURE 3, gas is introduced through gas inlet 48. During charging of the cartridge, the pressure within chambers 8 and 9 as well as in the spring chamber to the right of the valve is maintained substantially equal by virtue of passageway 17 in the base of valve 10 and passageways 30 in plate 29. Since the effective cross-sectional area at the right end of valve 10 is greater than its effective area on the left end, the valve is urged toward the left as gas pressure increases. Likewise, metallic seal ring 19 is also pressure responsive. However, since the effective cross-sectional area at the left end of this member is greater than at its right end, the seal ring is urged toward the right. Therefore, as the pressure within the cartridge approaches the predetermined discharge pressure, the metal-to-metal seal between valve 10 and metallic seal ring 19 becomes progressively greater. The diameter of O-ring 25 is less than the diameter of O-ring 20. Thus, the seal ring and valve, taken as a unit, has a resultant cross-sectional area which is larger on the left than on the right side. Therefore, as the pressure is increased, these members are forced to the right.

This sliding movement continues until the predetermined discharge pressure has been attained in chambers 8 and 9. Then metallic seal ring 19 is arrested in its action by shoulder 21 on sleeve 2 and extension 40 on pivot link 35 is moved by stop pin 41. Valve 10 because of its inertia continues movement to the right and causes a break in the seal between the valve and the metallic seal ring. Concurrently, extension 40 on pivot link 35 is forced into a clockwise direction by stationary stop pin 41. This action unlocks the linkage between disc 29 and spring plate 33. Thus, control spring 39 no longer exerts restraining force on valve 10. This sudden reduction in spring pressure on the valve coupled with the inertia of the valve facilitates breakage of the seal between the metallic seal ring and the valve. When this seal is broken, the compressed gas in second chamber 9 is rapidly vented through lateral vents 18 and exhaust ports 11, and the effective area of valve 10 in main chamber 8 is suddenly increased. These factors insure the rapid evacuation of compressed gas from second chamber 9 and the subsequent and substantially instantaneous opening of the valve at a greater velocity so as to permit the charge of gas within main chamber 8 to be suddenly and efficiently expelled through lateral exhaust ports 11. After the cartridge has been discharged, pivot link 35 is returned to its original locked position by tension spring 44 extending between pins 45 and 46 on the spring plate 33 and pivot link 35, respectively. Also, the valve and seal rings are urged to closed position by springs 12 and 39.

The embodiment of FIGURE 4 is also provided with triggering means but permits the employment of only one spring for operation of both the main valve and the triggering means. In this embodiment, disc 29 is held in place over the end of valve 10 by helical spring 12, and is provided with one or more perforations 30 to permit free passage of compressed gas therethrough. The disc is functionally connected to spring plate 33 by means of connecting link 34 and pivot link 35 in substantially the same manner as described above with regard to the embodiment of FIGURE 3. The connecting link is joined

to clevis 32 by pin 38 and to the pivot link 35 by pin 36, and the pivot link is rotatable about pin 37 through which it is attached to spring plate 33. Spring plate 33, which is positioned intermediate the ends of helical spring 12 is also provided with one or more orifices 47 to permit free passage of compressed gas therethrough.

While spring 12 is shown as a single spring, that portion of the spring 121 positioned between disc 29 and spring plate 33 can be a separate spring rather than a continuation of the main spring.

In the operation of the embodiment of FIGURE 4, compressed gas is introduced into main chamber 8 and passes through passageway 17 and about seal ring 19 into the second chamber 9 and thence through the perforations 30 and 47 in disc 29 and spring plate 33, respectively. Thus, the pressure, throughout the system is maintained substantially equal during charging. The effective areas on either side of the metallic seal ring and valve have substantially the same relationship as the same members in the embodiment illustrated in FIGURE 4. Here again, the sealing pressure between these two members increases with increased gas pressure. However, the diameter of seal 25 on valve 10 is less than the diameter of seal 20 on metallic seal ring 19. These two members thus slide to the right as the pressure is being built up with the cartridge. This movement of the valve also causes a like sliding movement of pivot link 35 and spring plate 33. The linkage continues moving to the right until extension 40 on pivot link 35 moves rigid stop pin 41 before metallic seal ring 19 contacts shoulder 21 of sleeve 2. The pivot link 35 is thus rotated in a clockwise direction about pin 37 and the linkage is unlocked at the predetermined discharge pressure by pin 36 being rotated to a position slightly above the axis defined by pins 37 and 38. With this unlocking of the linkage, the spring compression on plate 29 is released for a very short period of time, causing the inertia of valve 10 to force it to the right, breaking the seal between the valve and the metallic seal ring 19 and permitting the second chamber 9 to exhaust through lateral vents 18 in valve 10 and lateral exhaust ports 11. With this decrease in pressure in the second chamber 9, the force on the left hand side of the valve is tremendously greater than the force on its right hand side and the valve flies to the right, causing main chamber 8 to exhaust through the ports 11 and discharge the shell.

After discharge, the cartridge is returned to its original closed position by the action of helical spring 12 and 121 on valve 10 and on metallic seal ring 19. Also, the linkage is returned to a locked position by the force of spring 121 and the action of tension spring 44 extending between pin 45 on the spring plate 33 and pin 47 on pivot link 35. Thus, the cartridge of this embodiment is also fully automatic.

The embodiment of FIGURE 5 illustrates another means for breaking the seal between valve 10 and metallic seal ring 19 at the predetermined discharge pressure. In this embodiment, both the valve and the seal ring have larger effective areas toward main chamber 8 than toward second chamber 9 and the pressure in these two chambers is equated by gas passing between the ring and the valve through lateral vents 18 into the second chamber. Thus, as the pressure within the cartridge is increased, the valve 10 and ring 19 are moved to the right against helical spring 12. The base portion 16 of valve 10 is provided with a flanged member or a centrally positioned bolt 48 having an enlarged head portion 49. Metallic seal ring 19 is also provided with an internal flange 50 at the base thereof. One or more lever members or rods 51 engage head portion 49 of bolt 48 and flange 50 of seal ring 19 and are rotatable about fulcrum 52. As shown, fulcrum 52 is a pin passing through the main chamber 8 proximate the base of the valve and is suitably affixed to the main body 1. However, any other suitable means can be readily employed for rigidly positioning the fulcrum.

In the operation of this embodiment, compressed gas

is introduced into the main chamber. The gas pressure in the second chamber is maintained substantially equal to that in the main chamber, as previously described, by the gas passing between valve 10 and ring 19. As the gas pressure is increased within the cartridge, both the valve 10 and ring 19 are urged to the right compressing helical spring 12. As this sliding action continues, enlarged head portion 49 of bolt 50 engages the end portion of rod 51 causing it to rotate in a clockwise direction about fulcrum 52. This rotation causes the other end of rod 51 to move flange 50 on ring 19 forcing it to the left, and at the predetermined discharge pressure, effects separation of the valve from the seal ring. At this point, chamber 9 is evacuated as described hereinbefore, and the pressure in main chamber 8 forces valve 10 very rapidly to the right exposing lateral exhaust ports 11. Thus, the charge of compressed gas contained within main chamber 8 is suddenly liberated through the exhaust ports 11.

After being discharged, the valve and seal ring 19 are returned to their original position by the action of spring 12. As the valve returns to a closed position, it contacts the centrally located end of rod 51, returning it to its closed position at an angle substantially transverse to the longitudinal axis of the cartridge. The proportions of rod 51 on either side of fulcrum 52 can be readily modified to insure that the seal ring 19 will be separated from valve 10 at any point in the travel of the valve toward the right. This with the tension used on spring 12 provides a convenient method for modifying the discharge pressure of the cartridge.

The cartridge shown in FIGURE 6 is similar in some respects to the one shown in FIGURE 3 and previously described. However, the compressed gas in this embodiment does not pass to the right of valve 10. The valve is closed at one end by plug 49 which, for example, is screw threadedly inserted into the valve as shown at 50. The seal between the plug and the valve is completed by resilient O-ring 51. Pivot link 34 is connected to plug 49 through clevis 32 in the manner previously described.

When compressed gas is introduced into main chamber 8 through gas inlet 48, the gas passes into chamber 9 through openings 17 and 18 in valve 10. Thus, during charging of the cartridge, pressures in these two chambers are substantially equal. Since the pressure in the spring chamber to the right of plug 49 is substantially atmospheric, any increases in pressure within the cartridge causes sealing ring 19 and valve 10 to be urged to the right. These two members move as a unit toward end cap 5 until metallic sealing ring 19 is interrupted in its action by shoulder 21 on sleeve 2. The extension 40 on pivot link 35 is in contact with stop pin 41 and continued movement of valve 10 causes this pivot link to move in a clockwise direction and the pressure exerted on the valve by spring 39 is thus suddenly terminated. This reduction in spring pressure coupled with the inertia of valve 10 which is enhanced by the weight of plug 49 causes the metal-to-metal seal between the valve and the metallic seal ring to be broken. The relatively small amount of gas in second chamber 9 is thus rapidly vented through lateral vents 18 and exhaust ports 11, whereby the pressure in chamber 9 is reduced to a value well below that in chamber 8. Simultaneously, the effective cross-sectional area of the valve exposed to the pressure within chamber 8 is substantially increased. The valve is thus very rapidly opened and the gas within the cartridge is rapidly liberated, so as to provide a quasi-explosive effect. When the cartridge has discharged, it is returned to its original position by springs 12 and 39 as previously described in connection with the embodiment of FIGURE 3.

When the valve slides to the right the gas in the chamber accommodating springs 12 and 39 is slightly compressed, and thus offers slightly increasing resistance to the action of the valve. The effect of this compression is prac-

tically negligible and if desired can be eliminated by removal of O-ring 51 from about the outside diameter of valve 10. Then any gas trapped in the chamber can readily escape to the atmosphere through lateral discharge ports 11.

The discharge pressure of the cartridges of the present invention can be readily controlled by the strength of the main spring and also by the amount of tension on it which can be modified by adjustment of the position of end cap 5 with sleeve 2 or by inserting shims between the end cap and the spring. Also, the spring can be replaced by other suitable resilient means and various types of valves and linkage are readily adaptable to the cartridges of the present invention. In addition, the linkages shown in FIGURES 3 and 4 can be positioned completely within the valve when a shortened discharge portion is desired.

Although specific elements of the invention have been described in connection with particular embodiments, it will be readily understood that the various elements can be utilized in each of the various embodiments. For example, the lever means of FIGURES 3 and 4 can readily be incorporated with the valve structure of FIGURE 1. Also, the lever mechanism of FIGURE 5 can be used in conjunction with the trigger means shown in FIGURES 3 and 4.

While the invention has been described with particular reference to blasting or coal breaking cartridges, it will be readily appreciated that it is also applicable to any pressure release device in which a charge of compressed gas is suddenly liberated to act as a work performing medium. Such devices include metal working and shaping devices, cutting devices, power cartridges, and the like.

Although the invention has been described in considerable detail in the foregoing for the purpose of illustration, it is to be understood that such detail is solely for that purpose and that many modifications can be made without departing from the spirit and scope of the invention.

What is claimed is:

A valve device for explosively liberating a charge of compressed gas comprising a substantially cylindrical housing having a main chamber and an adjoining second chamber operative to contain gas under pressure, a lateral port in said housing, a slidably two-piece sleeve valve assembly in said housing said valve assembly including a main valve and a seal ring normally in abutting relation, said main valve including a head portion concentrically positioned in said seal ring, said head portion having lateral ports adapted to communicate with the lateral port in said housing upon separation of said main valve and said sealing ring, a passageway in said main valve to equalize pressure in said main and second chambers during charging, means cooperating with said housing and the valve assembly normally biasing and releasably holding the assembly in a position which closes the said housing port, said valve assembly having faces of differential area effective to cause said assembly to move as a unit in a first direction in response to fluid pressure impressed upon said faces, means cooperating with said housing and with said seal ring of said valve assembly operative to stop motion of said seal ring to break the unity of the assembly and thereby increase the effective differential area of said main valve, said main valve of the valve assembly being operative by virtue of its inertia and increased effective area to continue to move in said first direction effective to open said port.
